UNITED STATES PATENT OFFICE.

JOHN L. POLK, OF TROY, NEW YORK.

AUTOMATIC SWITCH.

1,007,386.

Specification of Letters Patent. Patented Oct. 31, 1911.

Application filed September 2, 1910. Serial No. 580,164.

To all whom it may concern:

Be it known that I, JOHN L. POLK, a citizen of the United States, and a resident of Troy, in the county of Rensselaer and State 5 of New York, have invented a new and Improved Automatic Switch, of which the following is a full, clear, and exact description.

My invention relates to automatic switches, my more particular purpose being to provide an automatic switch for controlling 10 electric currents, the switch in one of its movements being automatic, and also sluggish in its action.

More particularly stated, I provide a 15 switch having a lever movable by hand in one direction and movable in the opposite direction by the action of a spring and against the cushioning pressure of a dashpot for the purpose of retarding the movement or rendering it sluggish, the idea being that when the switch lever is in one of its extreme positions it closes one electric circuit and a few moments afterward opens that circuit and automatically closes another.

25 My invention is of special value in connection with internal combustion engines, such as are used upon automobiles, launches, aeroplanes and the like.

30 Reference is to be had to the accompanying drawings forming a part of this specification, in which similar characters of reference indicate corresponding parts in all the figures.

35 Figure 1 is a plan view of the switch complete, the lever occupying its extreme position to the left and closing one of the circuits; Fig. 2 shows the mechanism appearing in Fig. 1, the movable parts, however, 40 having shifted their position slightly and being upon their return to normal position; Fig. 3 is a section on the line 3—3 of Fig. 1, looking in the direction of the arrow; Fig. 4 is a fragmentary section substantially 45 on the line 4 of Fig. 3, looking in the direction of the arrow and showing the details of the dashpot; and Fig. 5 is a diagram of the wires and electric connections.

At 6 is a switch lever, made preferably of 50 metal and mounted to swing upon a pivot 7. The switch lever carries two contact blades 8, 9, separated from each other.

At 10, 11 are two contact buttons mounted 55 upon a block 10^a of insulating material. Two wires 12, 13 are connected with the contact buttons 10, 11. At 14, 15 are two

other contact buttons which are mounted upon a block 14^a and are insulated therefrom. Connected with these contact buttons are wires 16, 17.

60 The switch lever and various other parts are supported upon a plate 18.

At 19 is a plate connected by hinges 20 with one end of the switch lever 6 and adapted to swing relatively to the same. 65 The plate 19 constitutes practically a handle for the switch lever, though it has also other purposes hereinafter described.

70 Mounted rigidly upon the switch lever 6 are two bearings 21, 22 and extending through the latter is a sliding bar 23. A link 24 is connected with one end of this bar by aid of a pivot pin 25, and the opposite end of the link is, by aid of a pivot pin 26, connected with lugs 27, the latter being 75 rigidly mounted upon the plate 19. A leaf spring 28 is provided with a base 29 integral with it, this base being secured rigidly to the plate 18 by aid of screws 30. The sliding rod 23 is provided at its upper 80 end with a head 31, the latter carrying a pin 32 which normally engages the leaf spring 28. By grasping the handle 19 by hand and tilting its outer or free end upward, the sliding rod 23 is shifted into the 85 position indicated by dotted lines in Fig. 1, and in this event the guide pin 32 clears the leaf spring 28. This leaf spring bears against a pin 33 carried by the switch lever 6 and tends to swing the lever to the right 90 according to Figs. 1 and 2, provided the pin 32 is in engagement with the leaf spring 28, or in other words, provided the handle 19 occupies the position indicated in the figures just mentioned.

95 A latch 34 made of metal and provided with a laterally extending portion 34^a (being thus of substantially L shape) is mounted upon a pivot 35 carried by the switch lever. A tensile spring 36 is connected with the latch 34 and with the switch lever.

At 37 is a pin carried by the switch lever and at 38 is another pin carried by the sliding rod 23. The pin 38 normally engages the adjacent end of the latch 34.

105 Mounted upon the plate 18 is a fastening 40 and partially supported by the latter is a bellows 41 provided with heads 42, 43. Extending from the head 42 is a pin 44. The head 42 is provided with a valve 41^a opening inwardly and the head 43 is provided with a small air vent 43^a, which is adjust-

able by aid of a screw 43^b. By turning this screw to any desired extent, the operator may at will control the size of the air vent. The bellows and parts immediately associated with it together constitute a dashpot. A spring 45 is connected with the head 42 and normally tends to keep the dashpot distended, as will be understood from Fig. 1.

A leaf spring 19^a is mounted upon the 10 switch lever 6 and is provided with a bent portion which extends into an opening 19^b in the handle 19. The action of the spring 19^a is such that when the handle 19 is tilted upward—that is, into the position indicated 15 by dotted lines in Fig. 3—the spring in question will hold the handle in this position. The spring 45 is secured to a bolt 47 which is secured to the plate 18. The spring 45 normally tends to keep the dashpot distended, and to maintain the lever 6 in its 20 extreme position to the left according to Fig. 1, as shown in this figure. A stop pin 48 is also mounted upon this plate.

At 49 is an escutcheon mounted rigidly 25 upon the plate 18.

The handle 19 is provided with an extending portion 50 (see Fig. 3) carrying a bolt 51 which is slidably mounted in a compartment 52. Disposed within this compartment 30 and pressing against the bolt is a spring 53. Whenever the handle 19 is tilted, the portion 50 extends laterally from the switch lever 6 so that the bolt 51 may snap into the escutcheon 49 and thus hold the switch lever 35 stationary.

At 54 is an internal combustion engine and at 55 is one of the spark plugs for controlling the same.

At 56 is a magneto to which the wire 16 40 leads.

At 57 is a wire and at 58 is a spark coil, which is connected with the wire 57 by aid of a short wire 60. A wire 59 is also connected with the spark coil 58. The wires 45 57, 60 are connected with a wire 61, which leads to a battery 62. A wire 63 is connected with the wires 13, 17 and also with the spark plug 55. A wire 64 is connected with a timer 65 and this timer is in communication with the wires 59 and 61.

The operation of my device is as follows: Normally the parts are in the position indicated in Fig. 5. The contact blade 9 being in engagement with the contact buttons 14, 55 15, the so-called "magneto circuit" is now closed and may be traced as follows: magneto 56, wire 16, contact button 14, contact blade 9, contact button 15, wires 17, 63, spark plug 55, wire 64, timer 65, wire 59, 60 spark coil 58, wire 57, back to magneto 56. Suppose, now, that the internal combustion engine comes to a standstill and the operator wishes to start it into action. He grasps the handle 19 and by its aid swings 65 the switch lever 6 to the left according to

Figs. 1 and 2. The contact blade 9 is thus drawn out of engagement with the contact buttons 14, 15, and the contact blade 9 is moved into engagement with the contact buttons 10, 11. A battery circuit is now 70 completed and may be traced as follows: battery 62, wires 61, 60, coil 68, wire 59, timer 65, wire 64, spark plug 55, wires 63, 13, contact button 11, blade 8, contact button 10, wire 12, back to battery 62. This circuit (controllable by the timer 65) energizes the 75 spark plug 55. The length of the contact knife 8 being sufficient to enable it to extend to a considerable distance past the contact buttons 10, 11 (see Fig. 1), a considerable 80 retrograde movement of the switch lever 6 is necessary to disengage the contact blade 8 from its contact buttons. As soon as the switch lever 6 is moved to its limit to the left, according to Fig. 2, and is released, the 85 contact blade 8 begins to slide upon the contact members 10, 11, but nevertheless for a few moments maintains the battery circuit closed. During the movement of the switch lever 6 to the left, the portion 34^a of the 90 latch 34, by buffering the movement of the pin 44, allows the spring 45 to contact, thereby distending the dashpot to its full capacity, the pin 44 now occupying the position indicated in Fig. 1. When, therefore, after the 95 completion of the movement of the switch lever 6 to the left and the switch lever, under control of the leaf spring 28 is moving to the right according to Figs. 1 and 2, the portion 34^a of the latch 34 now lodges 100 against the pin 44 and the further movement of the switch lever 6 causes compression of the dashpot. The lever 6 now moves along at a snail's pace, the contact blade 8 thus remaining for a brief time in 105 engagement with the contact buttons 10, 11 (see Fig. 2). At last, when the dashpot is compressed considerably, the contact blade 8 leaves the contact buttons 10, 11 and a moment later the contact blade 9 engages 110 the contact buttons 14, 15. The battery circuit above traced is thus broken and the so-called magneto circuit is thus completed.

As may be seen from the foregoing description, the action of my device may thus 115 be summarized: The switch lever 6 being swung to the left by hand, the spark plug is energized for a little time by aid of the battery, and the brief time in question having elapsed, is energized by the magneto. 120 Since the magneto is not running while the machine as a whole is standing still, the use of the battery circuit for a short time—for even a few seconds—may be duly appreciated. When, however, the engine is once 125 in motion, the magneto circuit is far more satisfactory than the battery circuit and takes its place. Suppose, now, that the operator desires to throw out of action both the battery circuit and the magneto circuit. 130

Suppose, further, that he wishes to take precautions to prevent the shaking or accidental movement of any part from completing either one of these circuits. He grasps the handle 19 and by tilting it into the position indicated by dotted lines as above described and shown in Fig. 3, he also swings the switch lever 6 upon the pivot 7 as a center, moving the switch lever into such position that the portion 50 of the handle 19 is brought into registry with the escutcheon 49. The bolt 51 now snaps into the escutcheon and thus holds the switch lever 6 in such position that neither of the contact blades 8, 9 is in engagement with the contact buttons associated with it. In swinging the handle 19 into the position indicated by dotted lines in Fig. 3, the link 24 moves the sliding rod 23 in the general direction of the length of the latter, so that the head 31 is moved into the position indicated by dotted lines in Fig. 1, the pin 32 being thus moved out of engagement with the leaf spring 28. This renders the spring 28 practically useless for the moment and thus enables the lever 6 to be swung quite easily to its new position. The sparking apparatus as a whole is therefore thrown completely out of commission for the time being.

30. I do not limit myself to the precise form or shape shown for any of the parts. Neither

do I limit myself to the precise arrangement of the elements, the scope of my invention being commensurate with my claims.

Having thus described my invention, I claim as new and desire to secure by Letters Patent:

1. The combination of a contact lever, a spring for moving the same in one direction, a handle mounted upon said contact lever and movable relatively to the latter, and mechanism connected with said handle and with said contact lever for disengaging the latter from the control of said spring.

2. The combination of a circuit to be opened, a circuit to be closed, means including a movable member for opening said first mentioned circuit and closing said second mentioned circuit, actuating mechanism for shifting the position of said member, a handle carried by said movable member and connected with said actuating mechanism for disengaging said movable member from said actuating mechanism.

In testimony whereof I have signed my name to this specification in the presence of two subscribing witnesses:

JOHN L. POLK.
